UNITED STATES PATENT OFFICE

2,625,582

TUBE SOCKET

Jerome D. Heibel, Erie, Pa., assignor to Erie Resistor Corporation, Erie, Pa., a corporation of Pennsylvania

Application January 7, 1946, Serial No. 639,613

5 Claims. (Cl. 175—41)

1

This invention is intended to simplify the connection of condensers to vacuum tube elements by using tubular condensers in the tube socket around the socket terminals. This arrangement decreases the length of the circuit connections and also provides a shield around the terminals. In one form, one electrode of the condensers is connected to the mounting plate and in another form the connection is made to the center ground shield. These arrangements are particularly desirable for circuits in which the condensers are connected between the tube element and ground or between the tube element and some element of the apparatus circuit other than ground, as for example, plate to grid capacitative coupling.

In the drawings, Fig. 1 is a top plan view, partly broken away, of a tube socket showing tubular condensers surrounding two of the socket terminals and connected to a mounting plate; Fig. 2 is a sectional view on line 2—2 of Fig. 1; Fig. 3 is a sectional view through one of the tubular condensers; Fig. 4 is a sectional view through one of the socket terminals; Fig. 5 is a top plan view, partly broken away, of a modification in which the condensers are connected to the center ground shield; Fig. 6 is a section on line 6—6 of Fig. 5; Fig. 7 is a fragmentary section of a modification in which the tubular condensers and contacts are inserted from the bottom of the socket; and Fig. 8 is a fragmentary section of another modification in which the condenser is connected to a contact other than ground.

In the drawings, 1 indicates a mounting plate having a well 2 at the center with an inwardly extending flange 3 for receiving a base 4 of a tube socket. The well has indentations 5 which fit into complementary recesses in a mounting flange 6 on the base and hold the base against rotation. The base is held in the well by a plate 7 of the same general shape as the mounting plate projecting inwardly over the top of the mounting flange 6. The plates are secured together by tabs 8 on the plate 7 which are bent over the mounting plate. On the top of the base is a disc 9 of insulating material having holes 10 for receiving the base pins of a vacuum tube. At the center of the base is a non-circular opening 11 receiving the aligning plug of the vacuum tube. Within the opening 11 is a center ground shield 12a having lips 12 spun over the upper surface of the disc to hold it in place, and a lip 13 spun over a shoulder 14 on the base around the opening 11. At the lower end the center ground shield is provided with spring fingers 15 for locking the tube in the socket and with a ground terminal 16. 55 the pin receiving holes 10 is held in place by spun

2

Directly beneath the pin receiving holes 10 are recesses receiving pin engaging terminals 17 having integral strips 18 projecting through slots 19 in the base. These parts are or may be of common construction.

It is desirable that some of the base pins of the vacuum tube be connected to condensers and it is important that the condenser leads be kept short. For these base pins there are provided 10 enlarged recesses 20 receiving a tubular ceramic condenser 21 having an inner metal coating 22 surrounding and in contact with pin terminal 17 and an outer metal coating 23 in contact with tabs 24 extending through notches 25 in the side walls of the base. In order to insure good contact between the pin terminal and the condenser, the terminals are preferably made, as shown in Fig. 4, of sheet metal with a spring finger 26 in the part forming substantially a direct continuation of the strip 18 and with a spring finger 27 on each side which are folded toward each other to provide a roughly triangular opening for receiving the base pin. Below the fingers 26 and 27 are separate spring fingers 28 and a projection 29 which make contact with the inner metal coating 22 of the condenser. Because the spring fingers 28 are separate from the spring fingers 26 and 27 which contact the inserted pins on the vacuum tube base, the separate spring fingers 28 can be 25 proportioned to provide the proper contact pressure to the inner condenser electrode 22 and this contact pressure exerted by the fingers 28 will not be increased by the outward movement of the fingers 26, 27 such as would be produced by the 30 insertion of the vacuum tube base pin therebetween. This eliminates the danger of cracking the condenser elements.

The base may be constructed so that the condensers may be connected between each of the 40 pin receiving terminals and the mounting plate which will usually be grounded. The length of the condenser leads is obviously kept to a minimum since it consists of the spring contacts between the inner and outer condenser coatings.

45 In Fig. 5 and Fig. 6 is shown a modification in which the condensers are connected between the pin terminals and the center ground shield. As in the previously described construction, the base 4 is mounted in the well 2 of the mounting plate 50 1 and the mounting flange 6 rests on the inwardly extending flange 3 at the lower end of the well. The base is held in the well by lips 30 on the mounting plate which are spun over the upper edge of the mounting flange. The disc 9 with the pin receiving holes 10 is held in place by spun

over lips 12 on the center ground shield. Directly beneath the pin receiving holes 10 are the pin engaging contacts 17 surrounded by the ceramic condensers 21. The connection to the outer metal coating 23 of the condenser is made through a contact ring 31 seated on a projection 32 on the base and having spring fingers 33 extending through notches 34 in the base into contact with the outer metal coating 23 and having spring fingers 35 engaging the cylindrical portion 36 of the center ground shield. In other respects the socket construction is the same as that shown in Figs. 1 to 4 and corresponding parts are indicated by the same reference numerals.

In the construction so far described, the pin receiving terminals and condensers are assembled from the top and the assembly is completed by fastening the disc 9 in place.

In Fig. 7 is indicated an alternative construction in which the condensers and terminals are inserted from the bottom. In this construction the base 37 has a top wall 38 provided with pin receiving openings 39. Directly below the openings 39 are enlarged recesses 40 receiving the tubular ceramic condenser 21 and the pin contact 17. The recesses 40 are open at the bottom and are closed by a disc 41 having slots 42 receiving the strips 18 and held in place by spun over lips 43 on the center ground shield and by a snap ring 44. The contact with the outer condenser coating 23 is made by a contact ring 45 similar to the contact ring 31 and having contact fingers 46 engaging the condenser coating 23 and contact fingers 47 engaging the center ground shield.

In Fig. 8 is shown a modification of the Fig. 6 construction in which the base has one or more slots 48 receiving contacts 49 engaging the outer metallic surface 23 of the condenser 21. The contact has a spring finger 50 engaging a shoulder 51 at the bottom of the condenser receiving recesses. The contact also has a yieldable projection 52 making a tight fit between the contact and slot. The contact 49 is useful in connecting the tube element to another circuit element.

What I claim as new is:

1. In a tube socket of the type having, a base, pin receiving recesses, a tubular condenser in one of the recesses and having inner and outer electrode contact surfaces, a pin-engaging terminal within and contacting the inner surface of the condenser, an opening in the base providing access to the outer surface of the condenser, a center ground shield, and a connection from the shield engaging the outer surface of the condenser through said opening.

2. In a tube socket of the type having, a base, pin receiving recesses, a tubular condenser in one of the recesses and having inner and outer electrode contact surfaces, and a pin engaging ter-

45

5 minal within and contacting the inner surface of the condenser, the combination of a longitudinal slot in the base open at at least one end and intersecting and extending along the recess to provide access to the outer surface of the condenser, and a contact having a part in said slot engaging the outer surface of the condenser and a part extending out of the open end of said slot for connection to another circuit element.

10 3. In a tube socket of the type having, a base having circularly spaced pin receiving recesses having elements therein with parts making contact with inserted pins, the combination of a contact ring having spring fingers opposite and ex-

15 tends longitudinally of the recesses and of the axis of the ring, and longitudinal notches in the base receiving and locating the spring fingers, at least one of the notches having a depth sufficient to intersect the adjacent recess to provide an opening through which the spring finger extends into a contact making position within said recess.

20 4. In a tube socket of the type having, a base having a pin receiving recess with a pin contact therein, a tubular condenser surrounding the pin contact and having inner and outer electrode coatings, the combination of a longitudinal slot at one side and intersecting and extending along the recess, and a terminal in said slot having a spring finger bowed inward from the slot into engagement with the outer electrode coating of the condenser.

25 5. In a tube socket of the type having, a base having pin receiving recesses, a tubular condenser in one of the recesses and having inner and outer electrode contact surfaces, a pin engaging terminal within and contacting the inner surface of the condenser, the combination of a longitudinally extending notch at one side of and intersecting one recess to provide an opening into the recess, and a contact member having a spring finger received in the notch and engaging the outer surface of the condenser.
